UNITED STATES PATENT OFFICE.

ROSE LOMBARD, OF CORNELIA, GEORGIA.

DISH DRIER AND HOLDER.

1,351,577.

Specification of Letters Patent. Patented Aug. 31, 1920.

Application filed November 3, 1919. Serial No. 335,370.

To all whom it may concern:

Be it known that I, ROSE LOMBARD, a citizen of the United States, residing at Cornelia, in the county of Habersham and 5 State of Georgia, have invented certain new and useful Improvements in Dish Driers and Holders, of which the following is a specification.

This invention relates to a drier and 10 holder for dishes, the purpose being to provide an improved device which will obviate the necessity of wiping or drying dishes by the use of a cloth or tea-towel after washing and, further, to utilize the drier as a rack 15 or container so that the entire set of dried dishes may be set on a shelf or table, ready for use, if desired.

My invention is susceptible of embodiment in different forms of driers or holders with- 20 out departing from the principles thereof, but I have only described and illustrated two of the forms which the drier and holder may assume, one being for large plates, dishes, and small platters, and the other, 25 which is of smaller size, being particularly adapted for drying and holding smaller plates, cups, saucers, and dishes.

My dish drier and holder has a bottom which is arched or bowed so that the central 30 portion is higher than the sides; consequently, the dishes naturally gravitate toward the sides of the drier and holder and this enables the dishes to be arranged in two rows which rest against the sides of the drier and holder 35 and overlap in the central portion of the drier and holder, in staggered relation. By this arrangement, a very large number of dishes may be accommodated in a given drier and holder, whether it be the large or the 40 smaller size. Spacers or prongs or projections at the sides of the drier and holder are adapted to receive the outer edges of the dishes between them.

One or more coiled retainers are located 45 in the region of the arched bottom. The retainer has numerous coils and is adapted to shift in different directions as well as to contract or expand. In the larger size of the drier and holder there are preferably a plu- 50 rality of the coiled retainers arranged at the crest of the arch of the bottom. The smaller size of the drier and holder requires only a single coiled retainer. I do not, however, limit myself to the exact number of retainers 55 used in any particular embodiment of the invention or size thereof.

The bottom need not be in the form of a true arch, but it is of general bowed form. The bottom may be composed of wires, or, it may consist of a piece of block tin, or the 60 like, provided with suitable holes for draining. In either form, the coils of the retainer project above the general upper surface of the bottom.

In the accompanying drawings, 65

Figure 1 is an end elevation of the larger size of drier and holder, dishes being shown by dotted lines;

Fig. 2 is a plan view thereof;

Fig. 3 is an end elevation of a smaller size 70 of drier and holder, dishes and cups being shown by dotted lines;

Fig. 4 is a plan view thereof, certain parts being broken away;

Fig. 5 is a detail end elevation, broken 75 away, of a modification;

Fig. 6, a plan view thereof.

Referring first to Figs. 1, 2, 3, 4, the drier and holder is of basket-like form, the precise manner of constructing it not being 80 essential. As shown, it is made of wire. The bottom 1 is arched or bowed and the sides 2 have a general upright disposition, more or less outwardly flared or inclined as they proceed upwardly. Suitable handles 85 3 are provided for lifting the drier and holder and carrying it about.

As shown in Figs. 1, 3, 5, the bottom has a heavy marginal wire 4 and interlaced wires 5. There are upper and intermediate horizontal frames of heavy wire 6 and 7. At the corners are twisted stay wires 8. The sides comprise smaller wires 9.

Referring to Figs. 5, 6, the arched bottom may consist of the frame or marginal wire 95 4 and a sheet of block tin or other suitable material 10 provided with openings or perforations 11, the form thereof being arched or upwardly bowed.

Projecting from the intermediate frame 100 7 on opposite sides of the drier and above the lower ends of the arched bottom are prongs or fingers 12 which may be formed in any suitable, or preferred, manner and secured as desired, for instance, by the use 105 of inclosing tubes 13. These prongs provide means for holding the edges of the dishes which are shown in dotted lines at 14. The dishes are arranged in staggered or overlapped relationship and as the bottom of the drier is arched, the dishes naturally 110 gravitate toward the sides of the drier.

and are thus prevented from coming out of the spaces between the prongs.

To hold the lower portions of the dishes, one or more coiled retainers 15 are provided in the region of the upper part of the highest point of the arched bottom. Each retainer is, by preference, strung on a wire 16 connected to the bottom frame 4. This arrangement provides a support for the coils and prevents them from becoming displaced downwardly or laterally to such a degree that their usefulness might be impaired. I do not limit myself, however, except where so stated in the claims, to the use of the central wires. The coiled retainers 15 are of springy or resilient material and adapted to flex to a limited degree and to expand and contract. The coils are set relatively close together and yet sufficiently spaced apart to readily admit the edge of a plate, platter, saucer or other flat dish. These retainers enable the dishes to be lightly dropped or placed in the drier and to be held without especial attention being paid to how the dishes are placed, for the reason that with the numerous coils and their adaptability to flex and to expand and contract, the edge of the dish naturally seeks a space between two of the coils and, having entered therebetween, it is securely held inasmuch as its outer edge lies between the prongs 12.

Referring to Figs. 3, 4, a smaller size of the drier and holder is shown, the same being adapted for the accommodation of smaller plates, saucers and the like. Only one of the retainers 15 need be used. An arched bottom is provided which may be formed of wire or of a sheet of block tin as shown in Figs. 5, 6. Prongs or fingers 12^a are provided which may be secured in any suitable manner either to the intermediate frame 7, or, carried by a strip of folded sheet metal 17. In the smaller size of the drier and holder the upper frame 6 is made considerably larger than the intermediate frame 7 so that the upper part of the holder has sharply sloping walls 18.

Secured to the upper frame 6 are hooks 19 which are arranged so that when the handles of cups (shown in dotted lines at 20) are engaged therewith, the mouths of the cups face the inclined walls 18 and, hence, the water and suds are drained out of the cups. The other sides of the frame 6 may also have hooks of the same general character for the same purpose.

The dishes, cups, platters, knives, forks and spoons, as fast as washed, are placed in the proper drier and holder and the latter are then set on the drain board of the sink or shelf as desired and allowed to remain until the dishes, etc., have dried. Instead of removing the dishes, etc., from the respective driers and holders and placing them on shelves or any other containers,

they may be allowed to remain in the driers and holders and each drier and holder lifted by its handles and placed on the shelf until the dishes, etc., are again needed for use. This is rendered possible due to the manner in which the plates, cups and other dishes are held because they cannot accidentally knock against each other when the drier and holder is lifted and moved from place to place. 70

The spaced relationship of the cups, and dishes, when they are in the holders and driers, permits of the pouring of hot water thereover to sterilize them and facilitate the removal of suds or any adhering particles 80 of food.

The set of driers and holders disclosed in the drawings is adapted to hold a set of standard sized dishes for an average family. The largest size plate (standard set) exactly 85 fits the drier and holder of Figs. 1 and 2. One of the main advantages of the arched or bowed bottom of the drier and holder lies in the fact that as smaller plates are placed in position, they are forced to tilt 90 to the right or left and automatically seek a safety catch at the bottom and one side, due to the improvements hereinbefore described, whereas such smaller plates would naturally roll about laterally if the bottom 95 of the drier and holder were flat instead of bowed. Thus, I provide for the first time, I believe, a drying device which guards against danger of slippage and breakage in unpacking china or in placing 100 the drier and holder in the sink under a tap for rinsing, or, in carrying the filled drier and holder to the pantry or dining room. All other forms of dish driers and holders with which I am acquainted have 105 means whereby the china is stacked in a manner conducive to slipping in the process or removing from the drier, and none of them furnish a container which is safely portable when filled with dishes. 110

The driers and holders disclosed, respectively, in Figs. 1 and 2; 3 and 4; are proportioned so that they will nest one within the other for packing and shipping and for household use. The driers and holders furnish a complete outfit for the china used at the ordinary meal, the dimensions being worked out to that end. The drier and holder of Figs. 3 and 4 is adapted to nest in the drier and holder of Figs. 1 and 2. 115 120

The fundamental objection to the ordinary method of drying dishes without wiping is that the dishes, being piled against each other, drain onto each other. This drainage water, partly cooled, dries in 125 streaks. When dishes are placed in driers and holders constructed according to my present invention, the dishes are so tilted as to secure immediate drainage without draining onto any other piece, and expe- 130

- rience has shown that the dishes dry without streaks even if taken from soapy water without rinsing. The fact that the basket may be placed in the sink for final scalding or rinsing under the tap is an advantage as other driers are not thus portable. So far as I am aware, my dish driers and holders are the first which provide separated drying space for a standard set of dishes.
- 10 What I claim is:
1. A drier and holder for dishes having opposite outer sides or walls provided with dish-retaining means, said drier being provided with an upwardly bowed or arched bottom, and dish-engaging means located in the region of the bottom and adapted to engage the lower parts of dishes while the sides of said dishes are engaged by the dish-retaining means on the sides of the drier, 20 said bowed or arched bottom being adapted

to cause the dishes to gravitate toward the said outer sides or walls and thereby cause the dishes to be held by the dish-retaining means.

2. A rectangular drier and holder for 25 dishes whose opposite outer sides or walls are provided with dish-retaining means, said drier having an upwardly bowed or arched bottom extending from one of said walls to the other wall, and a coiled dish-retaining device located in the region of the bottom whose axis extends substantially parallel to the said sides which have the dish-retaining means, said bowed or arched bottom being adapted to cause the dishes to 30 35 gravitate toward the said outer sides or walls and thereby cause the dishes to be held by the dish-retaining means.

In testimony whereof I affix my signature.
ROSE LOMBARD.
